UNITED STATES PATENT OFFICE.

WILLIAM CLYDE BAXTER, OF BARTLESVILLE, OKLAHOMA; ROBERT D. WADDILL
ADMINISTRATOR OF SAID WILLIAM CLYDE BAXTER, DECEASED.

DIFFERENTIAL-PRESSURE GAGE.

1,292,418.

Specification of Letters Patent. Patented Jan. 28, 1913.

Application filed February 14, 1916, Serial No. 78,263. Renewed August 20, 1918, Serial No. 250,754.

To all whom it may concern:

Be it known that I, WILLIAM CLYDE BAXTER, residing at Bartlesville, in the county of Washington and State of Oklahoma, a citizen of the United States, have invented or discovered certain new and useful Improvements in Differential-Pressure Gages, of which improvements the following is a specification.

10 The invention described herein relates to certain improvements in differential pressure gages adapted to measure slight variations between two high fluid pressures and of the class or kind in which the recording 15 mechanism is actuated by a float carried by one of the columns of liquid variable in height in accordance with the differences of pressure exerted on the respective columns. As these gages have been heretofore constructed, an excessive pressure on one of the 20 columns of liquid would displace the liquid from both columns and render the gage inoperative until the liquid had been renewed. The object of the improvement hereinafter 25 more fully described and claimed, is to provide for the escape of fluid pressure from the chamber having the higher pressure, without destroying the seal between the two chambers, and for the automatic restoration of 30 operative conditions when pressure has dropped below a predetermined maximum.

In the accompanying drawing forming a part of this specification, Figure 1 is a view partly in section and partly in elevation, 35 showing my improvement applied to a differential pressure gage; Fig. 2 is a view similar to Fig. 1, of a different form of gage having the improvement applied thereto.

The gage shown in Fig. 1 consists of an 40 outer shell 1 provided with an inlet port 2, and an inner shell 3 having an external diameter substantially less than the internal diameter of the outer shell, and provided at its upper end with a flange 4 adapted to be 45 secured to the upper end of the shell 1, and close the annular chamber A, formed between the outer and inner shells. The open topped chamber B of the inner shell is connected by a passage 5, with a passage 6, 50 which is preferably formed by making the inner shell of such a length relative to the depth of the shell 1 that a small space is formed intermediate the shells.

The chambers A and B are charged with 55 a suitable liquid as for example, mercury to

a level below the inlet port 2. When the pressure of the fluid entering chamber A through port 2 exceeds that of the fluid in chamber B, liquid will be forced from the chamber A through passages 6 and 5 into chamber B, thereby raising the float 7, which is flexibly connected to one end of the arm 8 secured to the shaft 9. This shaft which is mounted in suitable bearings in the sides of the cap pieces 10, has its outer end operatively connected to a member of an indicating mechanism, as the pen arm 11.

As the pressure increases in chamber A, the liquid therein will be depressed until the pressure has attained a predetermined maximum. When this pressure has been attained, the level of the fluid will have passed below a port 12 leading to a vertical passage 13, having its discharge end above the level of liquid in chamber B at such maximum pressure. As soon as this port is uncovered the fluid will escape from chamber A forcing through the passage 13 the small quantity of the liquid contained therein. As soon as pressure in chamber A has dropped below the maximum, the liquid will flow back from chamber B into chamber A and the escape port will be submerged, and the operation of the gage become normal. As the escape port is above the passage 6, the seal formed by 85 the liquid in the latter will not be broken and the level of the liquid in the chamber B will remain at a height, corresponding to the predetermined maximum pressure in the chamber A at the time the escape port was opened.

In order to prevent any loss of the liquid employed in the gage, a deflecting plate 14 is arranged above the discharge end of the escape passage 13, and preferably a baffle plate 15 is arranged below and in line with the outlet 16 from the cap piece. Any liquid driven out of the passage 13 will flow back into the chamber B thereby increasing the height of liquid in chamber B from which it will flow back into chamber A, and as the pressure has been reduced in the latter the escape port 12 will be covered until the pressure in chamber A again exceeds the maximum.

In the construction shown in Fig. 2, the shells 1^a and 3^a have their lower ends connected by a passage 17 whereby the liquid can flow freely back and forth between the chambers according to the relative pressures 110

therein. The float 7 is carried by an arm 8 secured on the shaft 9, to which is also attached the pen arm 11 of the recording mechanism.

5 A tube 18 extends from a point above the connection of the passage 17 of chamber A, to a point in chamber B above the level of the liquid in the latter. The position of the lower or inlet end of this tube 18 10 will depend upon the desired maximum difference of pressure in the chamber, but in all cases the inlet to the tube should be above the point where the passage 17 connects with the chamber A, so that pressure 15 may be relieved before the seal formed by liquid in passage 17 is broken.

I claim herein as my invention:

1. In a differential pressure gage, the combination of two connected liquid containing chambers, a float arranged in one of said chambers, recording mechanism operative by the float and means permitting the escape of fluid from the high pressure chamber without forcing the liquid 25 from the normal connection between the chambers.

2. In a differential pressure gage, the combination of two connected liquid chambers, a float arranged in one of said chambers, recording mechanism operative by the float, means permitting of the escape of fluid from the high pressure chamber without forcing the liquid from the normal connections between the chambers and means 35 for returning to the float chamber liquid forced from the high pressure chamber.

3. In a differential pressure gage, the combination of two liquid containing chambers, a connection between the lower portions of said chambers, recording mechanism operative by the float, and a connection extending from a point below the normal level of the liquid in the high pressure chamber and adapted to deliver liquid 45 to the float chamber at a point above the level of the liquid therein.

4. In a differential pressure gage, the combination of two liquid containing chambers, a connection between the lower portions of said chambers, an outlet from the high pressure chamber arranged intermediate the level of the liquid in the high pressure chamber at minimum pressure and the point of connection with the low pressure 55 chamber, a float arranged in the low pressure chamber, and recording mechanism operative by the float.

5. In a differential pressure gage the combination of an outer shell, a removable 60 inner shell having an external diameter less

than the internal diameter of the outer shell, a passageway formed between the lower portions of the shells to permit the flow of liquid from the annular space between the shells into the inner shell, flanges 65 on the inner shell extending over the annular space between the shells and supported by the outer shell, a cap or cover for the inner shell, a float arranged in the inner shell, an indicator and connecting means 70 extending from the float through the cap to the indicator.

6. In a differential pressure gage the combination of an outer shell, a removable inner shell having an external diameter less 75 than the internal diameter of the outer shell, so arranged within the outer shell as to form an annular chamber exterior to the chamber formed by the inner shell, a passageway between the lower portions of the 80 chambers formed by said shells to permit the flow of liquid from the outer to the inner chamber, and supported by the outer shell, a passageway extending from the lower portion of the chamber formed by 85 the outer shell to a point above the normal level of liquid in the inner shell, a cap or cover extending over the inner shell, a float arranged in the inner shell, an indicator and connecting means extending from the float 90 through the cover to the indicator.

7. In a differential pressure gage the combination of an outer shell, a removable inner shell having an external diameter less 95 than the internal diameter of the outer shell, so arranged within the outer shell as to form an annular chamber exterior to the chamber formed by the inner shell, a connecting passage between the lower portions of the chambers formed by said shells to 100 permit of the flow of liquid from the outer to the inner chamber, flanges on the inner shell extending over the outer chamber and supported by the outer shell, a passageway extending from the lower portion of the 105 chamber formed by the outer shell to a point above the normal level of liquid in the inner shell, said passage having a port above the lower end of the inner shell for the escape of gas from the outer shell, a cover extending over the inner shell, a float arranged 110 in the inner shell, an indicator and connecting means extending from the float through the cover to the indicator.

In testimony whereof, I have hereunto set my hand.

WILLIAM CLYDE BAXTER.

Witnesses:

JAS. P. FISHER,

ERNEST O. HICKSTEIN.

It is hereby certified that Letters Patent No. 1,292,418, granted January 28, 1919, upon the application of William Clyde Baxter, of Bartlesville, Oklahoma, for an improvement in "Differential-Pressure Gages," were erroneously issued to Robert D. Waddill, administrator of said William Clyde Baxter, deceased, whereas said Letters Patent should have been issued to *Hope Baxter, administratrix of said William Clyde Baxter, deceased*, as shown by the record of assignments in this office; and that the said Letters Patent should be read with this correction therein that the same may conform to the record of the case in the Patent Office.

Signed and sealed this 25th day of February, A. D., 1919.

[SEAL.]

F. W. H. CLAY,

Acting Commissioner of Patents.
